UNITED STATES PATENT OFFICE.

GARDNER B. GRAY, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

TRACK-RELAY FOR SIGNAL SYSTEMS.

1,138,748.

Specification of Letters Patent. Patented May 11, 1915.

Application filed September 1, 1911. Serial No. 647,278.

To all whom it may concern:

Be it known that I, GARDNER B. GRAY, a citizen of the United States, residing at Pittsburgh, in the county of Allegheny and 5 State of Pennsylvania, have invented a new and useful Track-Relay for Signal Systems, of which the following is a specification.

The present invention relates to improvements in track relays, and the primary object of this invention is the provision or 10 production of a compound relay that is adapted to be disposed in a loop circuit around the insulated joint, as set forth in applicant's former Patent No. 909,083, granted to him January 5, 1909. This compound relay is used in place of the regular line relay and is made up of two neutral relays which work in combination to control a 15 polarity reversing switch, one of said relays being constantly energized with its polarity in the same direction, the other having its polarity reversed according to certain 20 conditions.

A further object of this invention is the 25 so mounting and constructing and assembling the various elements used in connection with this instrument as to produce a single instrument, that can be easily connected in place and in lieu of the regular line relay generally employed.

With the foregoing and other objects in view which will appear as the description proceeds, the invention resides in the combination and arrangement of parts and in 35 the details of construction hereinafter described and claimed, it being understood that changes in the precise embodiment of invention herein disclosed can be made within the scope of what is claimed without departing from the spirit of the invention.

In the drawings—Figure 1 is an enlarged detail view showing the core ends of the relays and the switch operated thereby. Fig. 2 is a view taken on line 7—7 of Fig. 1 looking 45 in the direction of the arrow.

5 indicates a plate for supporting the coils A, B and C which provide two neutral magnets or relays, the coils A A constituting one of the magnets and the coils B C 50 constituting the other of said magnets. The coils of each magnet are arranged side by side in parallel relation upon the upper face of the plate. The block 26 is secured to one pole of the magnet A A and is provided

with an orifice 27, in which an end 31 of the 55 armature 32 is pivoted by means of the spindle 30. The spindle 30 is removably and adjustably held in position in said orifice by the plate 28 and the adjusting screw 29.

Blocks F and G are secured to the cores 60 B' C', respectively, of the magnet B C and are formed with the arms 35 and 37 which extend in spaced relation parallel with said supporting plate 5 and toward block 26 of the magnet A A. Adjustably carried in the 65 terminals of said arms 35 and 37 are the contacts 34 and 36, respectively, between which the free end of the armature 32 extends. Depending from the supporting plate 5 is the plate 42 which supports below 70 the armature 32 the insulating block 41 having longitudinally formed therein the slot 41'. Secured to the lower face of the block 41 and on opposite sides of the slot 41' are the series of posts 45 and 46 which carry 75 pairs of carbon contacts 43' and 44' respectively. An insulating strip 39 is transversely secured to the armature 32 by the screw 38 and has the contact arms 40 and 40' suitably secured to the opposite end 80 thereof. These contact arms 40 and 40' extend substantially at right angles to the armature 32 and through the slot 41' and between the contacts 43' and 44'.

Current through the magnet A A is al- 85 ways of the same polarity and the armature 32 is polarized therefrom. Current through the magnet B C is adapted to be reversed through the existence of certain conditions and thus oscillates the armature between the 90 contact points 34 and 36. As the armature 32 is swung to or fro by the changing of the polarity in the magnet B C, the contact arms 40 and 40' are moved to engage with the respective sets of contacts 43' and 44' to close 95 certain circuits therethrough according to the movement of the armature 32.

What is claimed is:

1. The combination of two magnets, a metal block connected to one of the poles of 100 one of said magnets, an armature pivoted in said block and having its free end extended toward the poles of the other of said magnets, a metal block carried by each of the poles of the second magnet, terminals 105 formed on each of said blocks and disposed side by side in spaced relation to provide a space for the reception of the free end of the

- 2
- 14 armature, a plurality of depending contact arms carried by and insulated from the armature, a block of insulation through which said contact arms project and within which they are permitted to oscillate, and a plurality of contact points carried by and projecting below the block of insulation and in the path to be engaged by the contact arms, the change of polarity of the poles of said second magnet actuating the armature to cause it to move toward one or the other of said terminals and consequently actuate the contact arms to engage either set of contact points.
- 15 2. The combination of a supporting member, an armature carried on said supporting member, electromagnetic means on the support for influencing said armature and adapted to move the same in opposite directions, a plate extending from said supporting member, an insulating block secured to said plate and having a slot therein, sets of contact points mounted to the outer face of said block on opposite sides of the slot therein, contact arms secured to said armature and insulated therefrom and extended

through said slot to engage with certain sets of contact points to close certain circuits according to the movement of said armature.

3. The combination of relays having the coils of each arranged side by side, an armature having an end pivoted to one of the poles of one of said relays and being polarized thereby, arms extended from the poles of the other of said relays in spaced relation, the free end of said armature being extended between said extended arms and being adapted to be influenced by the polarity of the current therethrough so as to move therebetween, contact points arranged in spaced relation with said armature, and contact arms secured to the armature and insulated therefrom and to engage with certain of said contact points according to the movement of the armature.

In testimony that I claim the foregoing as my own, I have hereto affixed my signature in the presence of two witnesses.

GARDNER B. GRAY.
